UNITED STATES PATENT OFFICE.

JAMES H. BROOKMIRE, OF ST. LOUIS, MISSOURI.

APPARATUS FOR MIXING SUGAR.

SPECIFICATION forming part of Letters Patent No. 278,892, dated May 29, 1883.

Application filed October 13, 1882. (No model.)

To all whom it may concern:

Be it known that I, JAMES H. BROOKMIRE, a citizen of the United States, residing at St. Louis, in the State of Missouri, have invented 5 a new and useful Improved Apparatus for Mixing Sugar, of which the following is a specification.

The object of my invention is to mix sugar or different grades of sugar and produce a 10 product of thoroughly mixed particles or grades of sugar without injuring the quality thereof; and this object I attain by the mechanism illustrated in the accompanying drawings, in which—

15 Figure 1 represents my improvements as located and operating between two floors, the lower floor supporting the revolving table upon which the particles of sugar to be mixed in their fall drop and are centrifugally thrown 20 off from said table, as indicated by the arrows. The upper floor supports the feed-spouts through which the sugar is fed upon the table, and the lower floor has the hopper to receive the falling product and convey the same to 25 the final discharge, from which the product is packed into sacks, barrels, &c. Fig. 2 shows a top plan of the disk or table.

Similar letters refer to similar parts throughout the several views.

30 A represents the lower floor.
B represents the upper floor.

C represents the feed-spout through which from the upper floor the different grades of sugar to be mixed are fed in order to fall upon the revolving table, as indicated.

35 The upper floor has an opening, a, and in line therewith the feed-spout C is made pend-ent from the floor, as shown.

D represents the disk or table upon which, 40 as stated, the sugar falls in order to be sub-jected to centrifugal force, as will hereinafter appear. The table is simply a disk of wood, its upper face being horizontal, and by its socket d it is secured to the top of the vertical shaft E, the lower end of which is properly supported and connected to power source to 45 produce rapid revolution of the table and the sugar on top of same.

The space between the two floors can be

housed in on all sides, and the lower floor I 50 provide with the hopper F, its incline face f converging and leading the product to the final discharge spout G, as indicated.

Besides the stationary feed-spout C, the same has surrounding its lower end the movable 55 spout H, which can be raised or lowered by the cord or chain attachment h, passing over pulleys and within easy reach of the operator. By raising or lowering the outer spout, H, the distance between its lower end and the top of 60 the table can be increased or diminished, and the feed-passage regulated to suit the nature of the different grades of sugar, fine or coarse, as the case may be.

As shown in Fig. 1, the diameter of the flat 65 upper face of the revolving table or disk ex-ceeds the diameter of the feed-spouts, and said table is arranged on top of the shaft E and centrally in line with the feed-spouts, so that the delivery of the sugar can be directed 70 immediately to the center point of the upper face of the table, from which point the particles are thrown off tangentially over the face of the table to drop into the hopper below.

The mixer being thus constructed, its opera-tion is as follows: The sugar, or different grades thereof, to be mixed is fed from the top floor through the feed-spouts, as indicated by the arrows, Fig. 1. By gravity the said material falls down or through the said spout upon the 80 revolving table. As is apparent, as soon as the particles or sugar falls centrally upon the table the revolving motion of the latter, by virtue of centrifugal force imparted to the par-ticles or sugar, causes the same to fly or be 85 thrown outward and over or away from the table in the directions indicated by the arrows, Fig. 1. Each particle of sugar is thus acted upon by the centrifugal force produced by the rapidly-revolving table, and said particles are 90 thus subjected to a continual stir and mixing action until finally discharged into the hopper or receptacle below. The sack, barrel, or re-ceptacle is placed under the final discharge at G, when the mixed product is to be immedi-95 ately packed.

I do not claim, broadly, the telescopic feed-spouts to regulate the feed-passage; nor do I

claim, broadly, combining with said spouts a revolving shaft with a table or disk; but

What I claim is—

The combination of the feed-spouts C H, the 5 table or disk D, its shaft E, the hopper F, having inclined bottom, and the discharge-chute G, all said parts constructed and operating in the manner and for the purposes set forth.

In testimony of said invention I have hereunto set my hand.

JAMES H. BROOKMIRE.
